(57) **CLAIM**

The ornamental design for a pair of wireless smart earbuds, as shown and described.

DESCRIPTION

FIG. 1 is a front elevation view of the right wireless smart earbud of a pair of wireless smart earbuds showing our new design, the left wireless smart earbud being a mirror image thereof;

FIG. 2 is a rear elevation view of the right wireless smart earbud of the pair of wireless smart earbuds, the left wireless smart earbud being a mirror image thereof;

FIG. 3 is a right side elevation view of the right wireless smart earbud of the pair of wireless smart earbuds, the left wireless smart earbud being a mirror image thereof;

FIG. 4 is a left side elevation view of the right wireless smart earbud of the pair of wireless smart earbuds, the left wireless smart earbud being a mirror image thereof;

FIG. 5 is a top plan view of the right wireless smart earbud of the pair of wireless smart earbuds, the left wireless smart earbud being a mirror image thereof;

FIG. 6 is a bottom plan view of the right wireless smart earbud of the pair of wireless smart earbuds, the left wireless smart earbud being a mirror image thereof; and,

FIG. 7 is a perspective view of the right wireless smart earbud of the pair of wireless smart earbuds, the left wireless smart earbud being the opposite view thereof.
